CLAIM

The ornamental design for a cable tool, as shown and described.

DESCRIPTION

FIG. 1 is a perspective view of a cable tool showing our new design;

FIG. 2 is a front side elevational view thereof;

FIG. 3 is a rear side elevational view thereof;

FIG. 4 is a bottom elevational view thereof;

FIG. 5 is a top elevational view thereof;

FIG. 6 is a right end elevational view thereof; and,

FIG. 7 is a left end elevational view thereof.

The broken lines in the drawings represent unclaimed environmental subject matter.
